UNITED STATES PATENT OFFICE.

JOHN W. BARNHART, OF COLUMBUS, OHIO.

FIGURE WHEELED TOY.

1,424,437.

Specification of Letters Patent. Patented Aug. 1, 1922.

Application filed July 18, 1921. Serial No. 485,504.

To all whom it may concern:

Be it known that JOHN W. BARNHART, a citizen of the United States, residing at Columbus, in the county of Franklin and State 5 of Ohio, has invented certain new and useful Improvements in Figure Wheeled Toys, of which the following is a specification.

This invention relates broadly to toys, and has particular reference to the drawn or 10 hand pulled variety, the primary object being to provide a toy of a portable nature which will include a platform having an axle capable of rotating in unison with the supporting wheels of the toy, and to mount upon 15 the platform of the toy a plurality of mechanically operating devices simulating in appearance a Ferris wheel, an aerial swing and a diving structure, the said devices being connected by means of power imparting 20 drive connections so that upon movement on the part of the toy, the said axle will be rotated to impart movement simultaneously to all of the devices, whereby the latter will 25 present an animated appearance for amusement furnishing purposes.

With these and other objects in view, that will appear as the description proceeds, the invention further consists in the novel features of construction, combinations of elements and arrangements of parts, herein- 30 after to be fully described and particularly pointed out in the appended claims.

In the accompanying drawings:

Figure 1 is a perspective view of the im- 35 proved toy comprising the present invention.

Figure 2 is a vertical longitudinal sec- 40 tional view taken through the same.

Figure 3 is a transverse sectional view 45 taken on the line 3—3 of Figure 2, and,

Figure 4 is a similar view on the line 4—4 50 of Figure 2.

As shown in the accompanying drawings, my improved toy, which is designated in its entirety by the numeral 1, consists substan- 55 tially of a wagon, wherein is employed a box like body or platform 2, the said body includ- 60 ing a bottom 3 and upstanding side and end walls 4, the top thereof being left open. This body is supported upon sets of steering and 65 supporting wheels 5 and 6 respectively, the former being carried upon the ends of an axle 7, swiveled about a king bolt 8, and a handle or tongue 9 has its lower bifurcated end connected with the axle 7, so that the 70 wagon as a whole may be drawn and its 75 movements directed by manipulating the

tongue in the usual manner. The supporting wheels 6 are fixed to the ends of a drive axle 10, which is rotatably received within fixed bearings 11 depending from the body 2, and 60 by this construction it will be apparent that when the vehicle is drawn, rotation will be imparted to the axle 10.

Carried by the body of the vehicle is a plurality of devices simulating in appearance and in a miniature way many of the amusement furnishing devices found in recreational or amusement parks, for example, there is provided in the present instance a structure simulating a Ferris wheel 70 and designated in its entirety by the numeral 12; a second structure imitating an aerial swing, and designated by the numeral 13; and finally a structure resembling a diving platform, and designated in its entirety by 75 the numeral 14. These structures are adapted to operate from power derived from the axle 10.

To this end, the diving platform 14 consists essentially of a triangular frame 15, 80 having rollers 16 journaled in the three corners thereof, and around these rollers there is trained a flexible endless belt 17. The belt is provided in its outer surface and in spaced intervals with hinges 18, one leaf 85 of each thereof being rigidly connected with the belt proper while the other leaf is permitted to swing relatively to the belt and carries a plurality of life like figures 19 adapted to represent swimmers. One of the 90

rollers 16 has its shaft extending and provided with a double pulley 20 with which is engaged a drive belt 21, the latter extending upwardly through openings 22 provided in the bottom 3 from a pulley 23 fixed to the 95 axle 10. It will therefore be seen that in operation the rotation of the axle 10 will revolve the pulley 20 and the roller 16 associated therewith so that motion will be imparted to the belt 17. This causes the figures 19 to travel upwardly along the inclined run 24 of the frame 15 in an upright position until reaching the top of the frame. Then, by reason of the loose or freely movable leaves of the hinges 18, and by reason 100 of the weight of the figures 19, the latter will be caused to drop sharply so that they will extend parallel with the then downwardly moving run of the belt, and simulating thereby the appearance of a diver in the 110 act of executing a diving operation.

The aerial swing structure, designated by

the numeral 13, consists of a vertically extending mast 25, which is mounted for rotation in a bracket 26 carried by the bottom 3. The lower end of this mast is equipped 5 with a gear 27, which meshes with a pinion 28, also connected with the double pulley 20, the arrangement being such that when the vehicle is drawn, the gearing will be rotated so as to revolve the mast 25 and associated 10 structure. The upper end of the mast is formed with a collar 29 from which radiate arms 30 carrying at their outer ends fixed chairs 31, in which dolls or other life like figures may be seated, the top of the mast 15 being provided preferably with a flag 32. The rotation of the mast, by means of the mechanism described, results in causing the chairs 31 to revolve and to further assist in the development of the animated appearance 20 to the toy when in operation.

The Ferris wheel structure 12 includes an upright 33 which arises from the bottom 3, and to which is connected a frame in the form of a reel 34 to which is connected a 25 relatively enlarged pulley wheel 35. A bolt 36 is trained over the wheel 35 and also over one of the double pulleys 20, so that the rotation of the axle 10 will result in imparting rotation to the reel 34. The said reel, in 30 this instance, carries a plurality of cross rods 37, from which depend swinging chairs 38, also containing life like figures 39.

By reason of the construction described, my invention provides a toy which is believed to be capable of furnishing considerable amusement to children or those using the same, in that the rotation of the various structures carried by the toy will appeal to the youthful imagination and will be suitably ornamented and finished to attract and hold the eye. The device is of comparatively simple construction, is not likely to become out of order since the same involves 40 but few parts and arranged in such manner 45 that successful operation is assured. Movement is imparted by means of belts or cables

to the various structures employed by the toy and therefore by reason of these driving connections, chains, shafts and the like, which may readily become out of order, are 50 eliminated.

What is claimed is:

1. A toy comprising a body, supporting wheels, an axle rotatable with said wheels, a triangular driving frame carried by said body, and having one of its sides arranged perpendicular with respect to the bottom of the body, rollers journaled at the corners of said frame, an endless belt movable around said rollers, a driving connection between 55 one of said shafts and said rollers whereby the belt will be operated upon movement on the part of the vehicle, and a plurality of figures hinged to said belt and capable of extending parallel therewith when the belt is 60 moving along the perpendicular side of the frame and to extend at right angles to said belt when the latter is moving in an angular 65 upward direction.

2. A toy of the class described, comprising 70 a body provided with wheeled supporting axles, a mast rotatably mounted on the body and having a gear carried thereby, a triangular frame mounted thereon and having rollers in its corners, a belt trained around 75 the rollers, one of said rollers having a driving pulley associated therewith, a gear rotatable with the pulley and in mesh with the first named gear, a reel rotatably mounted on the frame and having a driven pulley 80 associated therewith, a belt trained around the driving and driven pulleys, a pulley fixed to one of the axles and having a pulley thereon, a belt trained around said pulley and the driving pulley for simultaneously imparting rotary movement to the 85 gears and respective pulleys to operate the amusement devices associated with the mast, reel and triangular frame.

In testimony whereof I affix my signature. 90

JOHN W. BARNHART.
